HYPODERMIC SYRINGE

Legan Eisele, Nashville, Tenn.

Application April 24, 1939, Serial No. 269,591

2 Claims. (Cl. 128—215)

This invention relates to hypodermic syringes and has for its primary object to provide means for establishing a reliable connection between the hypodermic needle and the syringe body, which connection will not separate in use but at the same time will be easily and quickly separable by the operator.

A further object of this invention is to provide a device of this character which is free from inaccessible dirt collecting crevices and which may thus be cleaned and sterilized properly.

A further object of this invention is to provide a device of this character which is capable of use with hypodermic syringe needles of standard types now available on the market.

A further object of this invention is to provide a device of this character which may be easily and cheaply manufactured, is of neat and pleasing appearance, and is not likely to get out of order.

The means by which these and other objects, which will later appear, are accomplished may be clearly understood by reference to the accompanying drawing, in which:

Figure 1 is a partial longitudinal section of a portion of a hypodermic syringe and needle incorporating my invention.

Figure 2 is a cross sectional view of the same taken along the line 2—2 of Figure 1, and

Figure 3 is a sectional view taken along the line 3—3 of Figure 2.

Referring now in greater detail to the drawing the numeral 10 indicates a syringe body, usually made of glass. A cap member 11, preferably made of metal is permanently attached by cementing, thermal contraction, welding or like means over the reduced portion 12 of body 10. Cap 11 is provided with an externally tapering discharge nozzle tip 13 adapted to receive the usual internally tapered needle hub 14 and form therewith a slip joint which is leak proof. Projecting from the outer face of cap 11, spaced from nozzle tip 13 and substantially parallel thereto is the projection 15 which has formed in its face adjacent nozzle tip 13 a depression 16 of the form of a portion of the internal surface of a frustum of a cone. The axis A of this frustum is spaced laterally from the longitudinal axis B of the syringe and is inclined to or forms a suitable angle with a plane normal to axis B.

This depression 16 is adapted to engage a corner 17 of flange 18 which is carried by practically all hypodermic needles now available on the market. In operation the hub 14 which carries the usual cannula 19 is placed upon the nozzle tip 13, the flat or cut-away portions 20 of the flange 18 passing by projection 15. When the tapers seat together, the hub is given a slight

twist relative to the nozzle tip 13 thus causing a corner 17 to pass into depression 16 and engage the surface thereof in such manner as to wedge the hub 14 upon the nozzle tip 13 in two directions. That is, due to the particularly contour of the internal surface of depression 16 of the hub 14 is urged radially against nozzle tip 13 and at the same time is urged longitudinally thereon. This double wedging effect has proved very advantageous and constitutes one of the chief features of the device.

Also due to the particular contour of the internal surface of the depression 16 a wide variety of sizes of needle hubs may be accommodated 15 some fitting further on the tapered nozzle tip 13, some turning through a greater angle before engaging the internal surface of depression 16, but all finding some point of engagement upon said surface and being wedged thereby, in two directions upon nozzle tip 13.

20 The removal of hub 14 simply requires a slight twist in a reverse direction whereupon corner 17 is caused to emerge from depression 16 whereupon hub 14 may be completely removed.

25 Since the device contains no hidden or inaccessible portions it may be very readily cleaned, sterilized and inspected.

While I have described a particular embodiment of my invention it will be apparent that a number of changes may be made in the actual production thereof without departing from the spirit of the invention as defined by the following claims.

I claim:

1. In a syringe, a cap carried upon one end of said syringe, a tapered nozzle projecting from said cap and adapted to receive a needle hub, a needle hub receivable upon said nozzle a projection carried upon said cap, spaced from and substantially parallel to said nozzle, said projection having formed in one face thereof a depression of the form of the internal surface of a frustum of a cone whose axis is spaced laterally from the longitudinal axis of the syringe and inclined with respect to a plane normal to said longitudinal axis of the syringe, said depression being adapted to engage a portion of said needle hub.

2. In a syringe, a tip for receiving a needle hub, a needle hub receivable upon said tip, retaining means for said needle hub comprising a retaining member spaced from and substantially parallel to said tip and having formed in one face thereof a depression of the form of the internal surface of a truncated cone, the axis of said depression being inclined to a plane normal to the axis of said tip, said depression being adapted to engage a portion of said needle hub.
